UNITED STATES PATENT OFFICE.

WILLIAM ROMÜNDER AND EDWARD J. FELLMAN, OF MILWAUKEE,
WISCONSIN.

DESIGN FOR A SEPARABLE HINGE.

SPECIFICATION forming part of Design No. 26,224, dated October 27, 1896.

Application filed February 13, 1896. Serial No. 579,181. Term of patent 14 years.

To all whom it may concern:

Be it known that we, WILLIAM ROMÜNDER and EDWARD J. FELLMAN, citizens of the United States, residing at Milwaukee, in the county of Milwaukee and State of Wisconsin, have invented and produced a new and original Design for Hinges; and we do hereby declare the following to be a full, clear, and exact description of the same, reference being had to the accompanying drawings, forming a part thereof, in which—

Figures 1 and 2 represent a front elevation of a hinge embodying our new design. Fig. 3 is a side elevation of said hinge, the upper end of the lower leaf being shown in section.

Our design relates to the new and original shape or configuration of the said hinge.

The leading features of our design comprise an upper leaf of much greater width than height and a lower leaf of much greater height than width, each part having a series of circular perforations. From the center of the lower line of the upper leaf is a projecting portion which extends downward in curved lines, comprising inward rounded lines from each side toward the center and a transverse semicircular line, which latter line is continued forward and upward at an ob-

tuse angle to the main body of said upper leaf, and this described projecting portion decreasing in width toward its upper free end and terminating in a nearly-flat though slightly-rounded end. The lower leaf is shaped with an offset near its upper end, so that the upper and lower portions of the leaf are both formed in straight vertical lines united by an oblique intermediate integral bend. The lower portion below said oblique bend is more than double the length vertically of the upper portion above said oblique bend, but the entire lower leaf is of an equal width throughout, and in said upper portion of the said lower leaf there is a rectangular straight-walled opening arranged transversely and of much greater width than height.

What we claim is—

The design for a hinge, substantially as shown and described.

In testimony whereof we affix our signatures in presence of two witnesses.

WILLIAM ROMÜNDER.
EDWARD J. FELLMAN.
